(57) CLAIM

The ornamental design for a sports theme air freshener, as shown and described.

DESCRIPTION

FIG. 1 is a front, top, and right side perspective view of a sports theme air freshener in accordance with the present disclosure;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

In the drawings, the broken lines depict portions of the sports theme air freshener and form now part of the claimed design. The sports theme air freshener is shown with symbolic breaks in the length of the cord elements. The appearance of any portion of the article between the break lines forms no part of the claimed design.
